UNITED STATES PATENT OFFICE.

WALTER M. DANN, OF WILKINSBURG, PENNSYLVANIA, ASSIGNOR TO WESTINGHOUSE ELECTRIC AND MANUFACTURING COMPANY, A CORPORATION OF PENNSYLVANIA.

TRANSFORMER.

1,289,406.

Specification of Letters Patent. Patented Dec. 31, 1918.

Application filed October 2, 1914. Serial No. 864,560.

To all whom it may concern:

Be it known that I, WALTER M. DANN, a citizen of the United States, and a resident of Wilkinsburg, in the county of Allegheny and State of Pennsylvania, have invented a new and useful Improvement in Transformers, of which the following is a specification.

My invention relates to transformers, and it has special reference to cooling means for power transformers of large capacity.

In air blast transformers, it is usual to direct cooling air in passageways that may be disposed between the various coils, the coils and the core members, and the core members and the inclosing casings. This type of construction necessitates the use of casings which entirely inclose the core structures, and, as a result, the weights of large kilowatt-capacity transformers are considerably increased because of the size of the casings required to inclose such transformers. Again, the air ducts between the coils and the core members must usually be large to furnish adequate ventilation, thereby effecting an increase in the length of the mean turas of the current-carrying coils and a consequent increase in the amount of copper required in the transformers.

By means of my invention, a transformer may be constructed which will weigh considerably less than a transformer of equal capacity and of the common type of construction. Another advantage usually accruing from the use of my invention is the high heat-radiating capacity which I secure while, at the same time, the air ducts between the coils and the core members may be substantially reduced in size or entirely eliminated. As a result, the amount of copper required may be considerably reduced.

It is frequently found in large-capacity air-blast transformers that certain portions of the laminations will become much hotter than other portions and it is, therefore, a further object of my invention to so construct a cooling means that the spots requiring the larger volume of cooling air will be supplied with such volumes while those portions which are relatively cool receive the smaller amounts of air.

The features which I believe to be novel and which characterize my invention are pointed out in the appended claims, while

the invention itself is exemplified in a structure that is described in the following specification and illustrated in the accompanying drawing, in which Figure 1 is a view, partially in elevation and partially in section, of a transformer embodying a form of my invention; Fig. 2 is a plan view of a portion of the bottom plate upon which the transformer coils and cores are supported, and deflectors attached thereto illustrating the manner in which said deflectors are operated to direct more or less air upon the laminations; and Fig. 3 is an elevational view taken on the line I—I of Fig. 2, some laminations being piled upon the bottom plate shown in Fig. 2.

Referring now more specifically to Fig. 1, a transformer of the shell-type construction rests upon a hollow cast metal base 1 which registers with an opening 2 of an air-pressure chamber that is always provided in conjunction with air-blast transformers. The core member 3, comprising a plurality of superposed laminæ, is provided with top and bottom end frames 4 and 5, respectively, the latter of which engages the upper rim of the base 1. A hollow metal top 6 is disposed on the upper end frame 4 and is provided with an air outlet opening 7 which may be closed by a hinged door 8. Tie rods 9 engage lugs 10 which are formed at the four corners of the end frame 4 and the top members 6, and are screwed into the lower end frame 5. Current-carrying coils 11 embrace a portion of the core members 3, longer legs 12 of the coils being inclosed by the core members, as is usual in shell-type construction.

Insulating strips 13, interposed between adjacent coils 11, provide air ducts between the coils by means of which cooling air blasts may traverse between the chambers inclosed by the top and bottom members 1 and 6. It will be noted that air ducts 14 and 15 are also provided between the coils and the core members. An air pressure is maintained in the chamber provided by the base 1 in order to promote the flow of air currents through the ventilating passages disposed in the active material of the transformer. By means of the hinged door 8, the flow of these air currents may be regulated. In certain cases, the air ducts disposed between the coils and my method of

cooling the core members 3 to dissipate the heat generated in the transformer may be relied upon, and the ducts 14 and 15 omitted.

5 The members 1 and 6 protect the exposed end portions of the coils 11. It will be noted that the core member 3 is not provided with an inclosing casing. Inasmuch as the heat generated within the core members 3 flows edgewise in the laminæ instead of through the faces of the laminæ, it will be seen that, by directly exposing the outer edges 16 of the laminæ to the outer air, the heat-radiating capacity of the transformer 10 may be greatly increased.

When the transformer is operating under load conditions, I have discovered that its heat-radiating capacity may be greatly enhanced by directing air currents transversely 15 across the directly exposed surfaces 16 of the laminated core in quantities dictated by the temperatures of the several sides of said core. To this end, I provide ports 17 in the end member 5, which are disposed adjacent 20 to the lower portion of the core member 3.

Adjustable vanes or deflectors 18 cover the ports 17 in order to regulate the flow of the air currents therethrough. Handles 18^a, attached to the deflectors 18, permit of regulating the air emitted from the ports 17.

It will be noted that through the medium 25 of the handles 18^a, the vanes or deflectors 18 can be moved to secure a larger or smaller opening whereby more or less air, as may be desired, can be directed upon the edges of the laminated structure. Since the several vanes 18, are therefore, separately, adjustable, it will be entirely possible to so direct 30 the air used as a cooling means that those portions of the laminated layers which are hottest will receive the larger volume of air.

Referring now to Figs. 2 and 3, the manner in which these vanes or deflectors 18 are operated, will be seen.

45 I will first describe Fig. 3 wherein the port 17 is shown as partially closed by the deflector 18 with which is operatively associated the handle 18^a. Rising from the plate 5 are lugs 19 provided with recesses 50 into which project pivots 20, said pivots being cast integrally with the vanes 18. By pressing downwardly on the handle 18^a, it will be observed that the vane 18 is revolved around the pivots 20 and thereby moved into 55 the position shown by the dotted lines. In this latter position the port is entirely uncovered, as shown.

In Fig. 2 I have illustrated the number 60 and relative positions of the deflectors 18 as used in my transformer. It will be observed that one vane is positioned in proximity to each side of the exposed portions of the laminated core, each of said deflectors or vanes being provided with a handle and independently operable as above described in

connection with Fig. 2 to allow more or less cooling air to be directed upon said exposed edges. All of the vanes are analogous in structure, operation, and relative position to that one shown at the right side of Fig. 2. 70

With the three vanes illustrated in the several positions of Fig. 2, it will be observed that different sized openings 21, 22 and 23 are provided through which the cooling air may be provided. The opening 21 is obtained when the handle 18^a and the vane 18 are in the position shown by the full lines of Fig. 3. If now, the vane 18 be rotated away from the lamination edges, an opening 22 as shown at 22 will be obtained. By further rotation of the vane 18 into the position indicated by the dotted lines in Fig. 3, the maximum opening 23 will be obtained. 75

It will be apparent, therefore, that the vane disposed in proximity to any side of the lamination edges may be so operated that a number of different openings may be provided through which more or less cooling air will be directed upon the said lamination edges. 80

While I have shown the transformer as having four sides and therefore provided with cooling air through the medium of four deflectors and four openings, one adjacent to each of the four sides, it is obvious that should a transformer of a greater number of sides be employed, all of said sides may be provided with independently operable deflectors for regulating the amount of air directed thereupon. 85

I have found that it is unnecessary to provide an inclosing casing around the core member 3 in order to confine the cooling air currents in close proximity to the core member for heat-conducting purposes. The air currents which are emitted from the ports 17 will flow upwardly and transversely across the exposed edges of the laminæ, there being an inherent tendency for these air currents to adhere closely to the laminæ along the entire length of the core member. The lugs 10 are so positioned at the top of the core member 3 in order not to impede the free flow of the air currents emitting from the ports 17. 90

From the foregoing description, it will be apparent that, by reason of the high heat-radiating capacity resulting from the direct exposure of the core member 3 to the outer air, and directing thereupon cooling air currents, my transformer may be operated under full-load conditions while insuring the maintenance of safe temperature rises in the active material of the transformer. At the same time, I eliminate the necessity of using 100 a casing which incloses the entire transformer inclusive of the core member.

While I have shown and described, somewhat in detail, a transformer built in accordance with my invention, it will be un- 105

derstood that many modifications may be made without departing from the scope and spirit of the appended claims.

I claim as my invention:

1. A transformer comprising current-carrying coils, core members therefor, the outer surfaces of which are exposed directly to the outer air, top and bottom members to inclose the end portions of the coils, and means to direct air currents upwardly and across the exposed surfaces of said core member, said means being so adjustable that varying quantities of cooling air may be directed against the sides of said core member.

2. A transformer, comprising current-carrying coils, core members therefor which comprise a plurality of superposed laminæ, the outer edges of which are directly exposed to the outer air, and a plurality of adjustable means to direct air currents upwardly and transversely across the exposed edges of said laminæ, said means being severally operable to direct volumes of cooling air across said exposed edges in quantities dictated by the temperatures of the various portions of said exposed laminæ.

3. A transformer comprising current-carrying coils, core members thereon which comprises a plurality of superposed laminæ the outer edges of which are exposed to the outer air, a hollow base member to support the core member, said base member being adapted to register with an opening of an air-pressure chamber and being provided with ports adjacent to the core member, and adjustable means severally associated with said ports and individually operable to open and close said ports, by means of which air currents may be directed transversely and upwardly across the exposed edges of said

laminæ as dictated by the temperature of said exposed portions.

4. A transformer comprising current-carrying coils, a core member therefor which comprises a plurality of superposed laminæ, the outer edges of which are directly exposed to the outer air, and a hollow base member to support said core member, said base member being adapted to register with an opening of an air pressure chamber and being provided with openings, said openings being so controlled that air may be directed upon the exposed faces of said core member in proportion to the degree of cooling required for said faces.

5. A transformer comprising coils, a laminated core having portions thereof embraced by said coils, the outer edges of the laminæ of said core being directly exposed to the outer air, a hollow base member engaging the core to support the active material of the transformer, said base member being adapted to register with an opening of an air-pressure chamber and provided with ports adjacent to the core member whereby air currents may be directed transversely and upwardly across the exposed edges of said laminæ, and adjustable means to severally regulate the flow of said air currents in quantities dictated by the temperatures of the various portions of said exposed laminæ, whereby those portions which are hotter may be supplied with the greater quantity of cooling air.

In testimony whereof, I have hereunto subscribed my name this 26th day of Sept., 1914.

WALTER M. DANN.
